ATTORNEYS

SNAP FASTENER ATTACHING APPARATUS

BACKGROUND OF THE INVENTION

1. Field of the Invention

The present invention relates to apparatus for attaching plastic snap fastener elements to an article of material and, more particularly, to such apparatus having multiple units of attaching machines.

2. Description of the Prior Art

U.S. Pat. Nos. 2,614,714; 2,735,567; 3,238,082 and 3,049,462 are representative of prior art apparatus for attaching snap fasteners to material. A cursory review of such prior art devices presents a clear indication of their extreme complexity and of their complicated operating mechanisms; in addition, none of such prior art devices have made any provisions for arranging their structures in such a manner to facilitate servicing and repair. The prior art devices are also deficient in any recognition or utilization of multiple units of attaching machines.

SUMMARY OF THE INVENTION

It is, therefore, an object of the present invention to arrange a plurality of snap fastener attaching machines into a unitary apparatus for performing a plurality of simultaneous operations.

The present invention is summarized in that apparatus for attaching snap fastener elements to an article of material includes a support base, a plurality of snap fastener attaching machines on the base with each machine having a resting portion and a mounting portion, a rest on the base engaged by each machine resting portion, a mount on the base cooperating with each machine mounting portion, and a clamping device adjustably clamping the mounting portion of each machine to the mount whereby each machine is selectively spaced from adjacent machines.

The present invention has another object in that a plurality of snap fastener attaching machines are separately adjustable on a supporting base.

It is another object of this invention to facilitate servicing, repairing and supplying apparatus embodying a plurality of snap fastener attaching machines.

Another object of this invention is to provide snap fastener attaching apparatus with a plurality of attaching machines that are individually pivoted on a support base.

A further object of the present invention is to construct multiple snap fastener attaching machines into a single unitary arrangement resulting in an extremely economical operation of an automated system.

Other objects and advantages of the present invention will become apparent from the following description of a preferred embodiment taken in conjunction with the accompanying drawing.

BRIEF DESCRIPTION OF THE DRAWING

The single FIGURE of the drawing is a partial isometric view of snap fastener attaching apparatus embodying the present invention.

DESCRIPTION OF THE PREFERRED EMBODIMENT

As is illustrated in the single FIGURE of the drawing, the present invention is embodied in apparatus including a plurality of machines for attaching plastic snap fasteners to any suitable material, such as an article of clothing where snap fasteners are utilized to close an opening in the article of clothing. The apparatus includes a flat support base 10 which may be a tabletop, stand or the upper surface of a cabinet. Adjacent its rear edge, the base 10 has an elongated strip or rest bar 12. A supporting bar in the form of a cylindrical rod 14 is mounted in spaced relation to the surface of base 10 adjacent its front edge by means of angle brackets 16 and 18, on each end of rod 14, which are fixed to base 10 by any suitable means, such as capscrews 19.

In the illustrated embodiment, four fastener attaching machines are utilized but any variety of multiple units may be used in accordance with the requirements of the particular fastening operations. These four machines, indicated generally at 20, 22, 24 and 26, respectively, are identical in construction so only the pertinent structure of one such machine is being described in detail. For example, the fastener attaching machine 20 has a generally rectangular boxlike configuration formed of relatively thin upper and lower hollow casings. The upper casing 30 has an opened top wall to receive a pair of snap fastener reels in side-by-side relation to each other. The snap fastener reel 32 comprises a continuous strip of plastic snap fastener backing elements 34 joined together by severable links; similarly, the snap fastener reel 36 comprises a continuous strip of plastic snap fastener stud elements 38 (or socket elements) joined together by severable links.

The upper casing 30 is fixedly supported on a similarly shaped lower casing 40 which contains the feeding, cutting and clamping mechanism for the two fastener elements 34 and 38; such mechanism is not being described in detail since any type may be utilized with the present invention. A pair of snap fastener chutes 42 and 44 project from the rear of casing 40 to receive the strips 34 and 38, respectively. The chutes 42 and 44 define spaced feeding guides for moving the strips 34 and 38 through the casing 40 to the front operating station 46 where the feeding, cutting and clamping operations are performed on the snap fasteners.

The operating station 46 includes feeding means for advancing the strips 34 and 38, means for cutting a single backing element and a single stud element (or socket elements) therefrom, respectively, and clamping means to clamp a backing element to a stud element with the cloth or garment material therebetween. The control system for activating the feeding, cutting and clamping mechanism may be of any suitable type, such as a pneumatic system utilizing an air cylinder 48.

As shown in the drawing the bottom rear edge of the casing 40 defines a resting portion which merely sits on the bar 12 while the front of the casing 40 defines a mounting portion which is supported on a mount in the form of a cylindrical rod 14. The lower front edge of casing 40 is provided with a hemispherical cutout so that it engages the rear half of the circumferential wall of the rod 14. A clamping block 50 has a similar hemispherical cutout so that it engages the front half of the circumferential wall of the rod 14. The clamping block 50 is attached to the front wall of casing 40 by a pair of capscrews 52 and 54 which transversely straddle the cylindrical rod 14.

The above arrangement has the particular advantage of permitting any one of the attaching machines 20, 22, 24 or 26 to be pivoted on the mount rod 14 so as to be displaced from the adjacent machines. For example, the end attaching machine 26 is shown in the drawing during such pivoted movement. Because the mount rod 14 is spaced above the surface of base 10, the machine 26 may be pivoted slightly beyond 90° so that it will rest on the edge of base 10; in such position, the sideplate of casing 40 may be removed whereupon the entire feeding, cutting and clamping mechanism is exposed for service, repair and/or replacement of parts. If it is desired to merely replace empty reels 32 and 36, the attaching machine 26 need only be pivoted to a suitable angle when the empty reels are readily removed and new reels inserted.

The four machines 20, 22, 24 and 26 are shown in the drawing as being equally spaced from each other so that upon insertion of a piece of material in the V-shaped openings defined by each operating station 46 permits simultaneous attachment of four pairs of snap fasteners (34 and 38 for each pair) to the material in equal spaced relation to each other. Such an operation is economically advantageous when plural snap fasteners are attached to a garment, e.g. a shirt, dress, jackets, etc. Of course, if more than four snap fasteners are desired, the apparatus is supplied with additional attaching machines.

It should also be noted that the four machines 20, 22, 24 and 26 are individually adjustable laterally on the mount rod

14 so as to be unevenly spaced from each other. With such an arrangement it is possible to space the four machines 20, 22, 24 and 26 from each other to accommodate any particular spacing that may be desired with respect to locating the snap fasteners on the material.

Inasmuch as the present invention is subject to many variations, modifications and changes in detail, it is intended that all matter contained in the foregoing description or shown in the accompanying drawing shall be interpreted as illustrative and not in a limiting sense.

I claim:

1. Apparatus for attaching snap fasteners to material comprising

a support base,

a plurality of snap fastener attaching machines on said base, each of said attaching machines having a resting portion and a mounting portion,

rest means on said support base engaging the resting portion of each attaching machine,

mounting means on said support base cooperating with the mounting portion of each attaching machine,

said mounting portion of each machine being movable relative to said mounting means permitting the resting portion of each machine to be movable relative to the rest means on said support base, and

clamping means adjustably clamping the mounting portion of each attaching machine to said mounting means whereby each attaching machine is selectively spaced from adjacent attaching machines.

2. Apparatus as recited in claim 1 wherein said clamping means includes a clamping block for each machine.

3. Apparatus as recited in claim 1 wherein the mounting portion of each machine is separately pivoted on said mounting means.

4. Apparatus as recited in claim 1 wherein said mounting means comprises a rod element engaged by the mounting por-

tion of each machine.

5. Apparatus as recited in claim 4 wherein said rod element includes end brackets to support said rod element in spaced relation to said base.

6. Apparatus as recited in claim 4 wherein said rod element is a cylindrically shaped rod and the mounting portion of each machine defines a pivoted connection with said rod whereby each machine is individually pivoted away from the other machines for servicing purposes.

10 7. Apparatus for attaching snap fasteners to material comprising

a support base,

a plurality of snap fastener attaching machines on said base, each of said attaching machines having a resting portion and a mounting portion,

rest means on said support base engaging the resting portion of each attaching machine,

mounting means including a cylindrically shaped rod on said support base and cooperating with the mounting portion of each attaching machine,

the mounting portion of each machine defining a pivoted connection with said rod whereby each machine is individually pivoted away from the other machines for servicing purposes, and

25 clamping means including a clamping block having a hemispherical recess partially encircling said rod and adjustably clamping the mounting portion of each machine to said rod whereby each attaching machine is selectively spaced from adjacent attaching machines.

30 8. Apparatus as recited in claim 7 wherein each machine has an open top wall for receiving reels of snap fasteners in continuous strips.

9. Apparatus as recited in claim 8 wherein each machine comprises a generally rectangular housing disposed in 35 edgewise fashion relative to said base.
